UNITED STATES PATENT OFFICE

JOHN D. MORGAN, OF SUMMIT, NEW JERSEY, AND HOBART N. DURHAM, OF JACKSON HEIGHTS, NEW YORK, ASSIGNORS TO SOUTHERN BRIGHTON MILLS, OF SHANNON, GEORGIA, A CORPORATION OF GEORGIA

LAUNDRY WORK UNIT

Application filed May 9, 1931. Serial No. 536,266.

The invention relates to new and useful improvements in laundry bag manufacturing and work units and fastening devices therefor, and more particularly to such bag closures and fastening devices comprising a cord or equivalent flexible constricting member.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawing, referred to herein and constituting a part hereof, illustrates one embodiment of the invention, and together with the description, serves to explain the principles of the invention.

Of the drawing:—

Fig. 1 is a fragmentary elevation of a laundry bag having a closure embodying the present invention;

Fig. 2 is a horizontal section, substantially on the line 2—2 of Fig. 1;

Fig. 3 is a detached end elevation of the cord-holding and locking device of the preceding figures, looking thereat from the right;

Fig. 4 is a detached isometric perspective view of the holding and fastening device; and

Fig. 5 is a plan view of a modified form of the fastening device.

The invention in certain of its aspects is in the nature of an improvement upon those of application Ser. No. 516,603, of Julian K. Morrison, filed February 18, 1931, and application Ser. No. 522,944 of the present applicants, filed March 16, 1931, but in other of its aspects it is otherwise applicable and useful.

One of the main objects of the present invention is to provide an improved manufacturing and work unit, comprising a laundry bag, preferably of netted fabric, and an improved

closure therefor attached to the bag and provided with holding and locking means whereby the bag is securely held tightly closed by merely pulling the fastening device tightly about the end of the bag, the closure and fastening means being of exceedingly simple and sturdy form, and capable of easy and quick closing and locking operation. The broader advantages of such a manufacturing and laundry work unit are set forth in the application of Julian K. Morrison herein-before referred to. The present invention has for one of its objects the providing of a closure which is sturdy and simple, which is easy and reliable in operation, and which requires little or no special manufacture of the parts or members of the closing and holding device. One object or purpose of the present invention is to provide a bag-constricting member, which is imperforate or non-apertured, the holding or locking device engaging the closure only externally to maintain the closure constricted about the bag.

In the present preferred and disclosed embodiment, the closure employed is a cord, such as sash cord, which in the case of the netted bag may be attached thereto by passing the cord through and tying it to the bag fabric, and if desired, about a side selvage of the bag material. Attached to the cord is an apertured metal fastener plate, and the cord or equivalent member is enlarged at the proper point or points, either by knotting it on itself or otherwise. The cord is slipped through an aperture in the fastener plate, and after being drawn tightly about the bag, it is slipped into the same or a different aperture in the plate, which is too small to pass the knot or enlargement, and by the engagement of such enlargement with the edges of the aperture the closure is held tightly constricted about the closed bag mouth.

Referring more in detail to the present preferred and exemplarily illustrated embodiment, a laundry bag 1 of any suitable fabric, and shown as having a netted or leno weave 2, has the open end thereof finished in any suitable way, as by an overcast stitching 3. The preferred form of closure comprises a cord, or other equivalent flexible member 7, 100

which may be an ordinary sash cord. This cord is preferably attached to the laundry bag, and as shown at 8, it is passed through and tied about the fabric of the bag. The 5 fastening device, as embodied, comprises a flat and curved metal plate 11, which is fastened to the member 7 by suitable means, and for this purpose it has near its rear end an aperture 12 and an external recess 13. As 10 shown, one end of the cord 7 is passed through the aperture 12, about the recess 13, and is knotted as shown at 14 in Fig. 2.

In the embodied form of closure holding and locking means, the cord or like flexible member 7 has enlargements thereon which during the bag closing operation automatically engage with the device 11 to lock or maintain the closure in its tight position. As shown, the cord has one or more knots 16 formed on itself at the proper point or points for holding the laundry bag tightly closed. The plate 11 has an aperture 17 sufficiently large to pass the knot or other enlargement 16, when the cord or equivalent closure 7 is threaded therethrough. An upset anti-friction part or tongue 18 is preferably formed at the front edge of the aperture 17 as a smooth bearing surface for the cord. In said preferred form, the device 11 has an aperture or recess so dimensioned and positioned that, when the bag has been tightly constricted, it will receive the cord or closure 7 just behind the enlargement or knot 16, and the enlargement or knot engaging with the front edges at either side of the slot or recess will maintain the closure in tightly-constricting position about the bag. As embodied, the plate 11 is provided with a forward extension 21, which is bent first upwardly and forwardly and then downwardly, and this extension has an internal aperture 22. The entire device 11 is preferably shaped so that it will conform to the curvature of the bag neck as constricted within the closure 7 and as shown in Fig. 2.

In operation, the closure 7 is passed about the neck of the bag and the free end is passed through the opening 17 of the fastener 11. The cord is then pulled tightly about the bag, 50 a very slight movement of the hand easing the enlargement or knot through the opening 17. The pull is backwardly, that is, oppositely from the direction of constriction of the closure 7 about the bag mouth, thereby enabling 55 the operator to grasp the closure within the fist and to use a full free-arm movement in pulling the closure tight. When the cord is drawn tightly the taut cord is simply lowered into the recess 22, and the enlargement 16 60 engages automatically on the outside of the member 21, and will hold the bag securely closed.

In Fig. 5 a modified form of the aperture 17 in the holding and locking device 11 is shown. In this form the cord or other clo-

sure 7 is slipped into the open side of the aperture 17, instead of being threaded there-through, and the operation is otherwise the same.

When desired to further lock, and preferably therewith to identify, the clothing within the laundry bag, a suitable device such as a spring snap hook 23 may be employed, and this may have an identification tag 25 fixed thereto, bearing a customer's identification mark such as the number 25. 70 75

The invention in its broader aspects is not limited to the specific mechanisms shown and described but departures may be made therefrom within the scope of the accompanying claims without departing from the principles of the invention and without sacrificing its chief advantages. 80

What we claim is:—

1. As a manufacturing and laundry work unit, a clothes holding bag, a constricting closure for the gathered bag end having an enlargement thereon, means attached to the closure and apertured to receive said enlargement to permit the closure to be drawn tightly about the bag and provided with a second aperture to engage and hold said enlargement to maintain the closure in its constricting position about the bag and means for closing said second aperture to secure said closure therewithin. 95

2. As a manufacturing and laundry work unit, a clothes holding bag, a constricting closure for the gathered bag end, means apertured to receive the closure to permit it to be drawn tightly about the bag and provided with a second aperture adapted to engage with the closure to maintain it in its tightly constricting position about the bag and identifying means adapted to secure the closure against release without removal of the identifying means.

3. As a manufacturing and laundry work unit, a clothes holding bag, a constricting closure for the gathered bag end tied through the bag fabric, means attached to the closure and apertured to receive the closure to permit it to be drawn tightly about the bag and provided with a second aperture adapted to engage with the closure to maintain it in its tightly constricting position about the bag and identifying means for closing said second aperture to secure said closure therewithin and prevent release without removal of the identifying means. 110

4. As a manufacturing and laundry work unit, a clothes holding bag, a knotted cord for constricting the end of the bag, a fastener apertured to receive the knotted cord to permit it to be tightly drawn about the bag and provided with a deep slot adapted to engage the cord behind a knot to maintain the cord in its tightly constricting position about the bag and removable identifying means for 130

closing said slot and securing said cord within
said slot and against release without removal
of said identifying means.

In testimony whereof, we have signed our
names to this specification.

JOHN D. MORGAN.
HOBART N. DURHAM.
